DESIGN FOR A SHOE BOTTOM

Shep C. Berkowitz, Los Angeles, Calif.

Application June 29, 1943, Serial No. 110,561

Term of patent 3½ years

To all whom it may concern:

Be it known that I, Shep C. Berkowitz, a citizen of the United States residing at Los Angeles, in the county of Los Angeles and State of California, have invented a new, original, and ornamental Design for a Shoe Bottom, of which the following is a specification, reference being had to the accompanying drawing, forming part thereof.

Fig. 1 is a bottom plan view;
Fig. 2 is a side elevational view; and
Fig. 3 is a front elevational view of a shoe bottom showing my new design.

I claim:
The ornamental design for a shoe bottom, as shown.

SHEP C. BERKOWITZ.
